(57) **CLAIM**

The ornamental design for an electric cleaning brush handle as shown and described.

DESCRIPTION

FIG. 1 is a top perspective view of an electric cleaning brush handle showing my new design;

FIG. 2 is a bottom perspective view thereof;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a top perspective view of the electric cleaning brush handle in an environment of use; and,

FIG. 10 is a top perspective view of the electric cleaning brush handle in another environment of use.

The dash-dash broken lines in the drawings illustrate portions of the electric cleaning brush handle that form no part of the claimed design.

1 Claim, 10 Drawing Sheets
